(57) **CLAIM**

The ornamental design for a blind hole mount post, as shown and described.

DESCRIPTION

FIG. 1 is a perspective view of a blind hole mount post, showing our new design;

FIG. 2 is a right side elevation view thereof, the left side elevation view of the blind hole mount post being identical;

FIG. 3 is a front elevation view thereof, the rear elevation view of the blind hole mount post being identical;

FIG. 4 is a top plan view thereof; and,

FIG. 5 is a bottom plan view thereof.

The broken lines are for the purpose of illustrating the environment of the article only and form no part of the claimed design.
